VAULT OR SAFE

James W. Mallonee, Joplin, Mo., assignor of one-third to Mattie E. McKee, Joplin, Mo., and one-third to Emma C. Drake, Lake Worth, Fla.

Application October 14, 1943, Serial No. 506,247

9 Claims. (Cl. 109—8)

This invention relates to a vault or safe for the protection of valuables, and has for the primary object the provision of a device of this character which besides providing the usual protection against robbery or unauthorized opening thereof, will have provision for trapping a robber therein and away from the valuables, should the robber intimidate a person having authorization to the vault or safe in the opening thereof and to bring about separation of the robber from said person and permit the escape of the person from both the robber and the device.

Another object of this invention is the provision of a device of the above stated character which is so constructed that a person being authorized in its use may enter and leave said device without danger of being trapped therein or causing an alarm of said device to be actuated.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a top plan view broken away and partly in section, illustrating a vault or safe constructed in accordance with my invention.

Figure 2 is a front elevation, partly in section, illustrating the device.

Figure 3 is a transverse sectional view illustrating a revolving door controlling the passage-way between compartments provided in the device.

Figure 4 is a fragmentary sectional view showing the trap door in a closed position and locked and the alarm actuated by the closing of the trap door.

Figure 5 is a fragmentary sectional view illustrating a locking element of a permutation lock employed on the revolving door and engaging its keeper.

Figure 6 is a view similar to Figure 5 showing the locking element disengaged from the keeper.

Figure 7 is a fragmentary sectional view showing a trip member operated by the rotation of the revolving door to release a locking pin for securing the door against movement after it has operated to cooperate with the trap door in trapping a burglar in the device.

Referring in detail to the drawings, the numeral 5 indicates the wall construction of the vault or safe and which is preferably construct-

ed of a double thickness suitably insulated, as shown at 6, for the protection of the contents of the vault from excessive heat in case of fire. The insulating material can be of any suitable kind and may be of a type to deaden sounds if desired.

The wall construction 5 provides the vault or safe of substantially rectangular shape and has in the front wall thereof a doorway 7 controlled by a door 8 mounted for hinging movement, as shown at 9, and held in a closed position by a permutation lock 10 operated from the exterior of the wall construction. Partitions 11, 12 and 13 are arranged within the wall construction to cooperate with a revolving door 14 in dividing the interior of the vault or safe into a compartment 15 in which valuables may be arranged and a vestibule 16. The revolving door controls the entrance between the vestibule and the compartment 15, the latter having a doorway 17 controlled by a secret door 18 which can only be opened from the interior of the vault or safe or from within the compartment 15. Any suitable securing means may be employed to prevent the door 18 from being opened from the exterior of the device.

Also for controlling the doorway 7 is a slidable trap door 19 arranged within the vestibule and when open is concealed from view. Coil-type expansion springs 20, set in the wall construction 5 of the device, act on the trap door 19 to urge the latter into position of closing the doorway 7. A locking pin 21 carried by a lever 22 is employed for releasably retaining the trap door normally in an open position. The lever 22 is pivotally mounted within a secret compartment 24 (see Figure 2) arranged in the ceiling or top wall construction of the device, with the pin 21 entering the vestibule to engage with the trap door 19 for retaining the latter in an open position.

The trap door 19 is also held in an open position by a treadle 25 concealed in the floor of the vestibule 16 and supported at one end by hinges 26 and further supported throughout its length by a series of coil springs 27 concealed within the floor (see Figures 1 and 2).

A suitable covering on the floor (not shown) is employed for concealing the treadle 25 from view and normally the treadle engages a keeper on the trap door 19 to prevent the sliding movement of said door under the influence of the springs 20. It will be seen that the treadle is of a skeleton frame construction covering considerable of the area of the floor of the vestibule, so that a person in order not to operate the treadle must

be familiar with its location in the floor of the vestibule when walking through the latter.

The revolving door 14 is journaled in the wall construction and includes a platform 27 carrying radially extending vertical panels 28 which will cooperate with the partitions 11, 12 and 13 in controlling the entrance between the vestibule 16 and the compartment 15. A driving spring 29 of the coil type is connected with the revolving door for the purpose of causing the latter to rotate in the direction indicated by the arrow in Figure 1, when said door is released from a locked position. A permutation type lock 29' is carried by one of the panels 28 of the door 14 to engage in a keeper carried by the partition 12 (see Figures 1 and 3) for locking the door against operation by the spring and in a position so that the panels will completely block or close the vestibule 16 off from the compartment 15.

The partition 28 on which the permutation lock 29' is mounted protrudes slightly beyond the other partitions of the revolving door and a stop 30 is arranged in the compartment 15 to be engaged by said longer panel when the door 14 is unlocked and thereby limiting the distance in which the door 14 will rotate under the action of the spring. The distance which the door 14 is allowed to rotate when released by the spring, is sufficient to carry a person standing on the platform of the door in front of the panel and operating the permutation lock 29', into the compartment 15 from the vestibule. The trailing panel 28 of the door behind the panel which carries the permutation lock 29' assumes a position opposite the partition 12 after the door has rotated as before stated, blocking or closing the vestibule to the compartment 15 and consequently preventing anyone else from following the person into the compartment 15.

To prevent the door from rotating in a reverse direction, one of the panels (that one rotatably ahead of the one carrying the permutation lock 29') is provided with a keeper 31 to receive a locking bolt 32 mounted in the ceiling of the device and free for sliding movement by gravitation when released by the pivotal movement of a spring influenced element 33 actuated by the rotation of the door, or one of its panels, so that the door after admitting the person to the compartment 15 cannot be rotated in either direction consequently preventing anyone within the vestibule from reaching the person within the compartment 15 or the valuables therein.

To operate the pin 21 for freeing the trap door 19 by the rotation of the revolving door 14, one of the panels 28 thereof strikes a pivoted lever 34 mounted in the ceiling and connected to the lever 22 by a link 35. Thus it will be seen as soon as the door 14 rotates to admit the person to the compartment 15 the pin 21 is withdrawn from the trap door allowing the springs 20 thereof to drive the trap door into a position of closing the entrance 9 trapping any person who may have followed into the vestibule the person who actuated or unlocked the door 14. Therefore, it will be seen that if a robber would intimidate a person having authorization to the device to enter said device and follow said person into the vestibule, the person authorized in the opening of the device when releasing the door 14 will stand on the platform of the door while the robber will stand on the floor of the vestibule and also on the treadle 25 to release the latter from the door 19. As soon as the person operates the lock of the door 14, said person is carried by the rota-

tion of the door into the compartment 15 the robber is blocked by the following panel of the door from following said person into the compartment.

As before stated, the door 14 automatically locks after a predetermined movement and cannot be rotated in either direction until released by a person familiar with the operation of the device in entirety. The robber cannot leave the vestibule either by way of the doorway 7, owing to the trap door 19 having moved into closed position, nor can he enter the compartment 15. The compartment 15 as soon as the door 14 rotates or operates the locking pin 21 will be illuminated by an electric lamp 37 arranged in the compartment 15. To bring about the automatic operation of the lamp 37 by the operation of the door 14, a switch 38 is electrically connected in the circuit of the electric lamp and to the link 35, so that when the link 35 moves to retract the pin 21 from the trap door 19 the circuit will be automatically closed to illuminate the lamp 37. Thus the person in the compartment 15 can readily see in order to operate the secret door 18 and escape leaving the burglar trapped within the vestibule.

When the door 19 moves into a position of closing the doorway 7 it strikes a lever 39 and imparts movement thereto (see Figure 4). The movement of the lever 39 actuates an alarm 40 of a conventional construction arranged exteriorly of the device for the purpose of attracting attention to persons in the vicinity of the vault or safe and indicating that a robber has been trapped therein.

The permutation lock 29' (see Figures 5 and 6) includes a locking element 41 mounted for rotation and which may enter a notch 42 of the partition 12 in securing the door 14 against rotation.

To prevent the trap door 19 from being opened from within, the vestibule 16 a gravity actuated pin 43 mounted in the ceiling of the wall construction 5 moves into a keeper 44 of the door 19 on the latter assuming closed position. This prevents the trapped burglar from working the door 19 into an open position for escape. Normally, the pin 43 is held elevated by the operating member 39 of the alarm 40. However, it will be seen that the door 19 moving into closed position slides the operating member 39 out of the way and thereby frees said pin 43 to enter the keeper 44 on the door assuming closed position.

To elevate the pins 32 and 43 operating elements 45 are connected thereto and extend through the ceiling of the wall construction for actuation from the outside of the wall construction 5 (see Figures 2, 3 and 4). Other types of operating means for the pins may be provided. This will permit freeing of the doors 14 and 19 for resetting of the vault or safe.

From the foregoing description taken in connection with the accompanying drawings, it will be seen that a vault or safe has been provided which will afford the usual protection to valuables against theft and also is provided with means for trapping a robber therein should the robber intimidate a person in the opening of the device. Also, it will be seen that the construction of the device is such that the person opening or gaining admittance to the valuable containing compartment will be admitted therein while the robber will be kept from entering said compartment and that the robber thus will be kept from escape by being entrapped in a vestibule arrangement which has its entrance automatically closed as soon as admittance of the

authorized person to the valuables compartment takes place.

Under normal conditions, a person authorized for the use of the safe or vault can enter the latter by opening the door 8 after operating the lock 10 thereon and walk through the vestibule without stepping on the treadle and take a position to operate the lock 29' which when actuated frees the door and allows the person to pass into the compartment 15. It is to be understood that the purpose of the treadle 25 is to release the trap door by the intruder or robber who is standing in rear of the person being forced to open or release the revolving door. Otherwise, when the door 14 is operated under normal conditions to admit the authorized person to the compartment 15 the trap door would be sprung or released for closing which is not desirable and only desirable in case of a robbery of the nature specified.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a vault, a closure divided into a valuable compartment and a vestibule having a doorway to the exterior of the closure, a revolving type lock controlled door for controlling the communication between said compartment and the vestibule, means for imparting rotation to said door when released, means for limiting the rotation of the door, means for preventing reverse rotation of the door after rotating in its initial direction, an automatic trap door for the doorway, means controlling closing of the trap door and including means operated by the revolving door, and also including means concealed within the floor of the vestibule for securing the trap door in an open position and operable under the weight of a person thereon to release said trap door, said last means being known to a person authorized to enter the closure so it may be avoided to prevent the trap door from closing on the operation of the revolving door by said authorized person.

2. In a vault, a closure having a doorway and provided with a valuable compartment, a revolving type door including radially extending panels and a platform for controlling access to said compartment, a locking means for said door operated from within the closure, spring means for rotating said door, a stop for limiting the rotation of the door, a locking means for automatically locking the door after a partial rotation thereof to admit an authorized person to said compartment, an automatic trap door for controlling the doorway, means for releasing the trap door for closing and including means operated by the rotation of said revolving door, and means for automatically locking the trap door in position of closing the doorway and releasable only from the exterior of the closure.

3. In a vault, a closure having a doorway and provided with a valuable compartment, a revolving type door including radially extending panels and a platform for controlling access to said compartment, a locking means for said door operated from within the closure, spring means for rotating said door, a stop for limiting the rotation of the door, a locking means for automatically locking the door after a partial rotation thereof to admit an authorized person to said compartment, an automatic trap door for controlling the

doorway, means for releasing the trap door for closing and including means operated by the rotation of said revolving door, means for automatically locking the trap door in position of closing the doorway and releasable only from the exterior of the closure, a treadle concealed in the floor of the closure and normally sustaining the automatic trap door in an open position and adapted to release the latter under a person's weight thereon.

4. A vault including a pair of doors controlling progressive entrance to the interior of the vault, said doors comprising a revolving door and a spring actuated sliding door, and catches securing the sliding door in open position and including a treadle release catch and a trip release catch, said trip release catch being actuated by a rotary movement of the revolving door.

5. A vault comprising a pair of doors controlling progressive entrance to the interior of the vault, said doors comprising a revolving door and a spring actuated sliding door, catches securing the sliding door in open position and including a treadle release catch and a trip release catch, said trip release catch being actuated by a rotary movement of the revolving door, spring means for imparting rotation to said revolving door, means for limiting the rotation of the revolving door, and means for preventing reverse rotation of the revolving door after rotating in its initial direction.

6. In a vault, a closure divided into a valuable compartment and a communicable vestibule, the latter having a doorway to the exterior of the closure, a revolving door for controlling the communication between said compartment and the vestibule, means constantly applied but normally restrained for imparting rotation to said door, means for limiting the rotation of the door in resistance to said door rotating means, means for preventing reverse rotation of the door after rotating in its initial direction, a normally open but self-closing automatic trap door for the doorway, means controlling closing of the trap door and including means operated by the revolving door and also including means concealed within the floor of the vestibule for securing the trap door in an open position but being operable under the weight of a person thereon to release said trap door, said last means being known to a person authorized to enter the closure so that said means may be avoided to prevent the trap door from closing on the operation of the revolving door by said authorized person.

7. In a vault, a closure divided into a valuable compartment and a vestibule, said compartment and said vestibule being intercommunicable, and the vestibule having a doorway to the exterior of the closure, a door for controlling the communication between said compartment and the vestibule, a normally open but self-closing automatic trap door for said doorway, means controlling closing of the trap door and including means operated by the first mentioned door and also including means concealed within the floor of the vestibule for releasably securing the trap door in an open position and being operable under the weight of a person thereon to release said trap door, said last means being known to a person authorized to enter the closure so that said means may be avoided to prevent the trap door from closing on the operation of the revolving door by said authorized person, and an alarm actuated by said trap door moving into position of closing the doorway.

8. In a vault, a closure divided into a valuable compartment and a vestibule, said compartment and said vestibule being intercommunicable, and the vestibule having a doorway to the exterior of the closure, a door for controlling the communication between said compartment and the vestibule, a normally open but self-closing automatic trap door for the doorway, means controlling the closure of the trap door and including means operated by the first-named door and also including means concealed within the floor of the vestibule for releasably securing the trap door in an open position and being operable under the weight of a person thereon to release the trap door, said last means being known to a person authorized to enter the closure so that said means may be avoided to prevent the trap door from closing on the operation of the revolving door by said authorized person, an alarm actuated by said trap door moving into position of closing the doorway, and means for automatically locking the trap door in a closed position.

9. In a vault, a closure divided into a valuable

compartments and a communicating vestibule and having a regular door affording access to said vestibule, a normally open but self-closing automatic trap door for the vestibule operated unknowingly by an unauthorized person entering the vestibule and also intentionally by an authorized person opening a door controlling communication between the valuable compartment and the vestibule, said controlling door between the valuable compartment and the vestibule being normally closed but self-opening upon releasable control of said authorized person, and opening a limited distance for immediate passage therethrough of the said authorized person but reclosing communication between said valuable compartment and said vestibule to prevent said unauthorized person from following the authorized person therethrough, and a secret door for the valuable compartment to permit the authorized person to escape from said compartment and whereby the unauthorized person is trapped and confined in the vestibule of the vault.

JAMES W. MALLONEE.
